SIGNALING SYSTEM.

1,073,835.

Specification of Letters Patent. Patented Sept. 16, 1913.

Application filed April 9, 1912. Serial No. 689,578.

To all whom it may concern:

Be it known that I, HERMAN W. DOUGHTY, of Binghamton, in the county of Broome and State of New York, have invented certain new and useful Improvements in Signaling Systems, of which the following is a specification.

My invention relates to signaling systems, and concerns particularly, improved means for cutting out of a circuit, mechanism located at a remote point and normally included in the circuit, as, for example, when tests of parts of the circuit are to be made. My invention can, of course, be applied in various ways; but, for illustration of its adaptability, I will describe it as applied in fire alarm systems. In fire alarm systems, normally closed circuits include a source of current and fire alarm boxes and also serially include main alarm mechanism, as, for example, striker controlling mechanism for tower bells or actuation control mechanism for whistles, etc. It is sometimes desirable to test out the line independently of the tower mechanism, but in present systems, if the tower mechanism circuit is disconnected, the current flow there-through would cease and the tower mechanism would relax and a false alarm would be given. In some cases, a separate source of current was substituted in the tower mechanism circuit before disconnection thereof from the main line. In other cases, it was necessary to climb up into the tower to prevent actuation of the alarm mechanism when disconnection from the main circuit was made.

The main purpose of my invention is, therefore, to provide means which can be controlled from the central station for disconnecting the tower service.

Another object is to provide simple mechanism, preferably electro-magnetically controlled mechanism, for controlling the remote mechanism to prevent false actuation thereof upon disconnection thereof from the main line.

In the accompanying drawings, the nature of my invention is fully disclosed and Figure 1 diagrammatically represents the main line with remote mechanism connected thereto and serially included in circuit with the main line to be responsive upon current changes. Fig. 2 illustrates one step in the cutting out of the remote mechanism and

connected from the main line current flow so that tests can be made of the main line equipment without influencing the remote mechanism.

The main line M serially includes the source of current S and any number of signaling stations B. The remote mechanism comprises an electro-magnet a, one terminal of whose winding connects through conductor b with the contact c connected with one branch of the main line and offering a contact for a switch lever d. The other terminal of the winding connects through conductor e with the switch lever d and connects through another conductor f with a contact g connected to the main line, the conductor f including the winding of a locking electro-magnet h. It is generally desirable that the resistance of magnet h should be approximately equal to that of magnet a, so that the substitution of one of these magnets for the other will not cause any material change of the current flow in the circuit. An intermediate dead contact i is also provided for the switch-arm d. The armature structure j for the electro-magnet a may control any mechanism. For example, it could mechanically control tower bell striking mechanism or whistle mechanism or it could control a local circuit k, including alarm mechanism l, as diagrammatically indicated. The electro-magnet h has an armature m engaged by retractile spring n, the armature when attracted being below a pin o at the end of the armature structure j, so as to prevent retraction movement of the armature structure j. However, when the armature m is retracted, the armature structure j is free to respond to makes and breaks in the main line M to control the local circuit K, to effect mechanical actuation of alarm or other mechanism.

Fig. 1 shows the normal conditions, the main line M serially including conductor b, windings of electro-magnet a and the conductor e, switch arm d being in engagement with contact g. Thus, normally, the locking electro-magnet h is short circuited by conductor e and its armature m is retracted so that the electro-magnet a can operate normally in correspondence with current changes in the main line. If, now, for example, it is desired to test on the main line independently of the remote mechanism, the switch lever d is first moved to the dead con-

tact *i*, whereupon the short circuit path *e* is broken and the locking electro-magnet *h* included serially in circuit in the main line with electro-magnet *a*. The armature *m* is then attracted below the pin *o* to lock the armature structure *j* in its attracted position, and we then have the arrangement shown in Fig. 2. The switch arm *d* is now moved into engagement with contact *c* as illustrated in Fig. 3, and the conductor *e* will short circuit the electro-magnet *a* and locking electro-magnet *h* will be retained serially in the main circuit. Upon such short circuit of the electro magnet *a*, the armature structure *j* will of course be released, locking armature *m* engaging below pin *o* so that the armature structure *j* cannot drop sufficiently to effect actuation of the alarm mechanism or to close the local circuit *k*. Tests may now be made on the main line without in any wise influencing the alarm electro-magnet *a* and the alarm mechanism controlled thereby, and false signals will be prevented. During testing, the main line may, of course, be opened, but the arrangement can be such that the pressure of the armature structure *j* on the locking armature *m* will be sufficient to prevent retraction of the locking armature when the circuit is open through its electro-magnet *h*; or the end of armature *m* may be provided with a small detent ridge *r* in front of which the pin *o* will engage, when the armature *m* is first attracted into locking position and the armature *m* thus held in locking position during current interruptions through electro-magnet *h*. While the electro-magnet *a* is normally intended to respond to impulses from the signaling stations for the purpose of properly controlling signaling mechanism, it is evident that the magnet *h* accomplishes no useful purpose by so responding, and said magnet *h* may therefore be constructed so as to act more sluggishly than magnet *a* so that if the main line is opened while switch lever *d* is resting upon the dead contact *i* (as shown in Fig. 2) the pin *o* will be dropped within the path of the detent ridge *r* before the armature *m* has moved in response to its retractile spring *n* out of the path of said pin *o*, thus holding the armature structure *j* against dropping sufficiently to affect actuation of the alarm mechanism controlled by it. After test has been made, the switch lever *d* is again restored to normal position in engagement with contact *g*, whereupon armature structure *j* is again attracted and the short circuit *e* restored to the locking electro-magnet, whose armature *m* then falls back into retracted position, whereafter the armature structure *j* is free for normal operation to respond to signaling impulses through the main line.

65 As before stated, the adaptation of the

invention is not limited to fire alarm or allied systems, but can be usefully applied anywhere where it is desired to control remote mechanism and to prevent certain actuation thereof when current flow is withdrawn therefrom.

Changes and modifications are also possible in the arrangements which I have shown and described and would come within the scope of the invention, and I therefore claim the following:

1. In an electrical system, the combination of a normally closed main circuit, a branch circuit extending to a remote point and serially connected with said main circuit, an electro-magnet device in said branch circuit having an armature, mechanism controlled by said armature, a locking electro-magnet having an armature and having its winding included in said branch circuit, the armature of said locking electro-magnet being adapted to lock the electro-magnet device armature against retraction upon energization of said locking electro-magnet, switch mechanism associated with the main circuit, and a conductor connected with said switch mechanism and said branch circuit, said switch mechanism when in one position causing said conductor to short-circuit said locking electro-magnet, and when in another position disconnecting said conductor from circuit so that current may flow through both said electro-magnet device and the locking electro-magnet, and said switch mechanism when in a third position causing said conductor to short-circuit said electro-magnet device.

2. In an electrical system, the combination of a normally closed serial circuit comprising a main loop and a branch loop extending to a remote point, a source of current for said closed circuit, a main electro-magnet having its winding included in said branch loop and having an armature, mechanism controlled upon retraction of said armature, a locking electro-magnet having an armature adapted when attracted to prevent retraction of the main electro-magnet armature, the winding of said locking electro-magnet being adapted for serial inclusion in said branch loop, a conductor normally short-circuiting said locking electro-magnet, and switch mechanism for disconnecting said conductor from said locking electro-magnet to allow energization thereof and to bridge said conductor about said main electro-magnet to cause deenergization thereof.

3. In an electrical system, the combination of a normally closed circuit having a loop extending therefrom to a remote point, a source of current for said closed circuit, a main electro-magnet in said loop circuit having an armature, signaling mechanism controlled upon retraction of said armature, a locking electro-magnet included in said

loop circuit and having an armature adapted when attracted to prevent retraction of the main electro-magnet armature, and switch mechanism connected with said loop circuit and adapted when in one position to cause short-circuiting of said locking electro-magnet, and when in another position to cause inclusion of both electro-magnets in circuit, and when moved to a third position 10 to cause short-circuiting of the main electro-magnet.

4. In an electrical system, the combination of a normally closed circuit having a branch circuit extending therefrom and in serial relation therewith, a source of current in said main circuit, a main electro-magnet in said branch circuit having an armature, signaling mechanism controlled by said armature, a locking electro-magnet 15 included in said branch circuit in series with said main electro-magnet, a switch arm adapted for connecting with the terminals of said branch circuit, and a conductor connecting said switch arm with the branch circuit at a point intermediate of said main electro-magnet and said locking electro-magnet, said locking electro-magnet having an armature adapted when attracted to lock the armature of the main electro-magnet.

5. In an electrical system, the combination of a normally closed circuit, a source of current for said circuit, a main electro-magnet included in said circuit and having an armature, signaling mechanism controlled 30 upon retraction of said armature, a locking electro-magnet included in said circuit and having an armature adapted when attracted to coöperate with the main electro-magnet armature to prevent retraction thereof, an auxiliary conductor, and switch mechanism adapted when in one position to connect said auxiliary conductor in bridge of the locking electro-magnet to prevent energization thereof, said switch mechanism when 35 in another position causing dis-connection of said conductor from circuit whereby both electro-magnets may be energized, and said switch mechanism when in another position causing connection of said conductor in 40 bridge of the main electro-magnet to cause deenergization thereof.

6. An electric circuit comprising a source of current, transmitting devices, and an electromagnet controlling signaling mechanism, 55 means whereby an electromagnetic locking mechanism for said signaling mechanism may be substituted for a part of said circuit, and means whereby the substituted part of said circuit may subsequently be substituted for said controlling electromagnet.

7. An electric circuit comprising a source of current, transmitting devices, and an electro-magnet controlling signaling mechanism, an electromagnetic mechanism for locking 65 said signaling mechanism which may be sub-

stituted for a part of said circuit to lock the signaling mechanism, and means whereby the substituted part of said circuit may be substituted for said signal controlling electromagnet to cause deenergization thereof. 70

8. In an electric circuit containing a source of current and transmitting devices, a loop extending from said circuit and having three conductors, one of said conductors containing an electromagnetic signaling mechanism, another of said conductors containing an electromagnetic locking mechanism for said signaling mechanism, and means for connecting the third conductor in shunt with either one of the other two 75 conductors.

9. In an electric circuit containing a source of current and transmitting devices, a loop extending from said circuit and having three conductors, signaling mechanism, an electro-magnet for said signaling mechanism connected in one of said conductors, locking mechanism for said signaling mechanism, an electromagnet for said locking mechanism connected in another of said conductors, the 80 third conductor adapted to be connected in shunt with either of the other two conductors to deenergize the electromagnet therein.

10. In an electric circuit containing a source of current and transmitting devices, 85 a loop extending from said circuit and having three conductors, signaling mechanism, an electromagnet for said signaling mechanism connected in one of said conductors, locking mechanism for said signaling mechanism, an electromagnet for said locking mechanism connected in another of said conductors and normally deenergized by being shunted by the third conductor, means whereby the locking magnet may be energized to lock the signaling mechanism by the opening of the shunt formed by the third conductor, and means whereby the signaling magnet may be deenergized by the closing of a shunt formed by the third conductor. 100

11. In an electric circuit containing a source of current and transmitting devices, a loop extending from said circuit and having three conductors, one of said conductors 115 containing an electromagnetic signaling mechanism, another of said conductors containing an electromagnetic locking mechanism for said signaling mechanism, the third conductor extending to the junction of 120 the other conductors, and means for connecting the third conductor in series with either one of the other two conductors.

12. In an electric circuit containing a source of current and transmitting devices, 125 a three-conductor loop extending from said circuit, one of said conductors containing an electromagnetic signaling mechanism, another of said conductors containing an electromagnetic locking mechanism for said sig- 130

- 4
- naling mechanism, the third conductor containing relatively low resistance and means for connecting any two of the conductors in series.
5. 13. In an electric circuit containing a source of current and transmitting devices, a loop extending from said circuit and having three conductors, one of said conductors containing an electromagnetic signaling mechanism, another of said conductors containing an electromagnetic locking mechanism for said signaling mechanism, the third conductor extending to the junction of the other conductors, and means for connecting the third conductor in series with either one of the other two conductors and at the same time in shunt with the other one of the two conductors.
10. 14. In a normally closed signaling circuit, a source of current, transmitting devices, a relatively rapid electromagnetic signaling mechanism normally in circuit, a relatively sluggish electromagnetic locking mechanism normally in circuit but having a shunt whereby said locking electromagnet is rendered inoperative, and means for removing said shunt to energize the locking electromagnet to lock the signaling mechanism.
15. 15. In an electrical system, the combination of a normally closed main circuit, a branch circuit connected with said main circuit to receive current flow therefrom, a main electromagnet included in said branch
- circuit to receive current flow therefrom and having an armature, mechanism controlled by said armature, a locking electromagnet having an armature adapted when attracted to lock the main relay armature in attracted position, a shunt circuit normally connected to prevent current flow through said locking electromagnet, and switch mechanism for opening said shunt circuit.
16. In an electrical system, the combination of a normally closed main circuit, a branch circuit connected with said main circuit to receive current flow therefrom, a main electro-magnet included in said branch circuit to receive current flow therefrom and having an armature, mechanism controlled by said armature, a locking electromagnet having an armature adapted when attracted to lock the main relay armature in attracted position, a shunt circuit normally connected to prevent current flow through said locking electromagnet, and switch mechanism for removing said shunt circuit from said locking electromagnet to allow energization thereof and locking by its armature of the main relay armature and for closing said shunt around said main electromagnet.
45. 50. 55. 60. 65.

In witness whereof, I hereunto subscribe my name, this 5th day of April A. D., 1912.
